[54] BAR-STOCK GUIDE ARRANGEMENT FOR A
SWISS-TYPE AUTOMATIC LATHE
2 Claims, 3 Drawing Figs.

[52] U.S. Cl. 82/38

ABSTRACT: The bar-stock guide housing is divided into upper and lower parts, the upper part being free to swing upwards, permitting the housing to be opened up for sideways loading of the bar stock.

Sheet 1 of 2

FIG. 1

Sheet 2 of 2FIG. 2

FIG. 3

BAR-STOCK GUIDE ARRANGEMENT FOR A SWISS-TYPE AUTOMATIC LATHE

BACKGROUND OF THE INVENTION

The invention relates to a bar-stock guide arrangement on a "Swiss"-type automatic lathe, including a tubular housing, a plurality of supporting rods within the housing and extending lengthwise thereof, and a plurality of elastic bar-stock guides mounted on the rods and spaced along the lengths thereof.

SUMMARY OF THE INVENTION

An object of the invention is an improved guide arrangement of this kind which is quieter in operation and more easily used.

This object and others of the invention will be apparent from the following detailed description.

BRIEF DESCRIPTION OF THE DRAWINGS

The invention will be described, with reference to the FIGS. of the accompanying drawings, wherein:

FIG. 1 is a longitudinal section of the guide arrangement of the invention;

FIG. 2 is a cross section taken along line II-II of FIG. 1; and

FIG. 3 is a view of another cross section of the arrangement.

DESCRIPTION OF THE PREFERRED EMBODIMENT

The illustrated bar-stock guide arrangement, for use on a Swiss bush-type automatic screw machine, comprises a tubular housing that is cross-sectionally divided into an upper part 1 and a lower part 2. These two parts have a U-shaped cross section, as shown in FIGS. 2 and 3.

The lower part 2 is fastened to supports 3; and the upper part 1 is fixed to swivel arms 4, of which only one is shown. These arms are so mounted on pivot pins 5, fixed to the supports 3, that the upper part 1 can swing upwards about an axis parallel to the longitudinal axis of the housing.

A series of support pieces 6 are simply placed in the upper part 1. Fastening pieces 7 are fixed in the upper part by individual screws 8, which also serve to attach the arms 4 to the housing upper part 1. Two supporting rods 9 extend along the

length of the housing through holes in the parts 6 and 7. The portions of these rods between the parts 6 and 7 hold the ends of elastic bar-stock guides 10. These guides have an arcuate middle section, as seen in FIG. 2, and are advantageously injection molded and made from a glass-fiber strengthened polyamide.

Similar supporting rods 9a, support pieces 6a, and fastening pieces 7a are provided in the housing lower part 2 and positioned opposite the corresponding parts 6, 7 and 8.

10 The usual bar-stock ram, incorporating a flag 12 on its rear end, is indicated by the reference number 11.

15 Each pair of guides 10 and 10a forms a portion of a straight bar-stock guide channel, which can be opened up, because the housing upper part 1, along with the parts it holds, is free to swing upwards, permitting the bar-stock to be loaded sideways (rather than longitudinally, as at present) into the guide channel.

20 Although the preferred embodiment of the invention has been described, the scope of, and the breadth of protection afforded to, the invention are limited solely by the appended claims.

I claim:

1. A bar-stock guide arrangement on a Swiss-type automatic lathe, including a tubular housing, a plurality of supporting rods within said housing and extending lengthwise thereof, a plurality of elastic bar-stock guides mounted on said rods and spaced along the lengths thereof to form a bar-stock guide channel, and wherein the improvement comprises that said housing in cross section is divided into upper and lower parts, said upper part being free to swing upwards with respect to said lower part for opening up said housing and the bar-stock guide channel and permitting sideways loading thereof with bar-stock, and wherein said supporting rods and said elastic guides are divided in number between said housing upper and lower parts, and said elastic guides therein are positioned opposite each other.

2. The bar-stock guide arrangement as defined in claim 1, wherein said supporting rods and elastic guides are equally divided in number between said housing upper and lower parts and those said rods and guides in said housing upper part move therewith when the latter swings upwards.
